UNITED STATES PATENT OFFICE.

JOHN DEEBLE, OF SOUTHBINGHAM, CONNECTICUT.

NAIL-PULLER.

SPECIFICATION forming part of Letters Patent No. 644,667, dated March 6, 1900.

Application filed November 15, 1899. Serial No. 737,074. (No model.)

To all whom it may concern:

Be it known that I, JOHN DEEBLE, a citizen of the United States, residing in Southington, in the county of Hartford and State 5 of Connecticut, have invented certain new and useful Improvements in Nail-Pullers, of which the following is a specification.

My invention relates to improvements in nail-pullers; and the objects of my improvement are simplicity and economy in construction and general efficiency of the article.

In the accompanying drawings, Figure 1 is a side elevation of my nail-puller with the foot-lever in vertical and longitudinal section.

Fig. 2 is an edge view of the same looking on the pivotal end of the foot-lever. Fig. 3 is a sectional plan of the same on the line *x x* of Fig. 1.

A designates the body of the main lever, 20 upon which an ordinary sliding hammer (not shown) may be fitted in any ordinary manner. Extending downwardly from the said body there are two integral spring-arms 4 4, that terminate in the pointed jaws 5 6, of which 25 the jaw 5 may be of any ordinary form and to which jaw the foot-lever B is pivoted by the pin or bolt 8. The jaw 6 has on its outer edge, a short distance above its lower end, a shoulder 9, above which shoulder is an incline 10, that is eccentric to the pivotal bolt 8 of the foot-lever, as shown in Fig. 1. The foot-lever is, in the main, of an ordinary form and is bifurcated at one end, so as to receive and embrace the two jaws 5 6 between its 30 arms, as shown. The wall at the end of the bifurcated portion of the foot-lever that faces the eccentric face or incline 10 of the jaw 6 may be made so as to substantially conform to that face when the lower edge 7 of said 35 lever bears upon the shoulder 9, as shown in Fig. 1. The body A and spring-arms 4 4, together with the jaws 5 and 6, are of a flat plate-like form, whereby they may be cheaply constructed as one integral thing by cutting 40 from a bar of rolled steel. They may also be cut or formed with the pointed ends of the jaws farther apart than is desired when in 45 the position for use, so that in order to mount the foot-lever thereon in the manner shown 50 it will be necessary to force them together a little, so that when thus mounted the foot-lever will hold the jaws under tension. This

will cause the lower edge 7 of the foot-lever to bear with pressure against the shoulder 9 and prevent the said foot-lever from accidentally falling down over or off from the end of the jaw 6.

In use the jaws are placed in proper position over the head of the nail to be drawn and then driven into the wood slightly. The body 60 A of the main lever is then forced toward the outer end of the foot-lever, which foot-lever by engaging the surface of the wood moves on its pivot against the incline 10 and forces the jaws firmly upon the nail, after which a 65 continued movement of the body of the main lever in the same direction will draw the nail. Upon returning the lever to release it the resiliency of the arms 4 4 spreads them apart until the edge 7 of the foot-lever is engaged 70 with the shoulder 9, as shown.

It is apparent that some changes from the specific construction herein disclosed may be made, and therefore I do not wish to be understood as limiting myself to the precise form 75 of construction shown and described, but desire the liberty to make such changes in working my invention as may fairly come within the spirit and scope of the same.

I am aware that a prior patent shows and 80 describes a nail-puller having integral spring-jaws of a flat plate-like form and with a slotted footed lever through which the lower ends of the jaws pass, the said lever being pivoted to one of said jaws, while the wall at the end 85 of the slot in the said lever bears against the inclined outer edge of the opposite jaw; also, that another patent shows and describes a similar nail-puller, but with the foot-lever having in addition to the jaw-receiving slot 90 an inclined slot on each side that is engaged by a pin or stud on one of the jaws for forcing the jaws together and for holding the foot-lever in position without any engagement 95 whatever with the outer edges of the jaws. All of the above prior art is hereby disclaimed.

By my improvement a very durable and efficient implement is produced in which the wearing-surface is confined mainly to the outer edge of the jaw, while at the same time 100 the foot-lever is held in place thereon with the jaws under tension. The implement can also be constructed at a small cost without any additional expense over the more simple form

of implement first disclaimed and without any frail parts that are liable to be soon impaired in use.

I claim as my invention—

5 The combination of the arms 4, 4, and jaws 5, 6, one of said jaws having the shoulder 9 and incline 10, with the foot-lever pivoted to

the jaw 5 and bearing on the incline and shoulder of the opposite jaw, substantially as described.

JOHN DEEBLE.
